UNITED STATES PATENT OFFICE

NIELS A. CHRISTENSEN, OF MILWAUKEE, WISCONSIN

COMPRESSOR GOVERNOR

Application filed July 18, 1924. Serial No. 726,876.

The invention relates to compressed air systems, and more particularly to the governor or control of a continuously running compressor.

5 One type of governing means for compressors is that in which mechanism is provided for automatically holding the inlet valve of the compressor open during the compressing stroke, the mechanism being directly associated with the inlet valve for this purpose. In some installations it is not feasible to associate the governor means of the compressor with the inlet valve because of the location of the compressor relative to 10 other parts associated with it or with the engine for driving it. The object of this invention is to provide a compressor governor of the automatic pressure relief type which may be placed in any suitable position in the discharge line of the compressor between the discharge valve and the reservoir, thereby permitting the device to be readily installed without consideration of the design of other parts of the compressing apparatus or its 15 driving means.

The invention further consists in the several features hereinafter set forth, and more particularly defined by claims at the conclusion hereof.

20 In the drawings: Fig. 1 is a side elevation view of a compressor governor embodying the invention, parts being broken away and parts being shown in section;

Fig. 2 is a plan view taken of the structure 25 shown in Fig. 1, with the top cover removed;

Fig. 3 is a sectional view taken on the line 3—3 of Fig. 2, showing the parts of the governor in one position;

Fig. 4 is a view similar to Fig. 3 showing 30 the parts of the governor in another position.

The device embodying the invention may be used in connection with any suitable compressor and is shown as associated with the discharge pipe 5 from said compressor which 45 conducts the compressed air to the reservoir, not shown, past the usual check valve 6 in the discharge pipe. The governor herein-after explained is designed to provide a valve-controlled vent opening from the discharge 50 pipe 5, or an equivalent part leading to the

reservoir, so as to provide a vent opening whereby when the pressure in the reservoir reaches a predetermined maximum the continuously running compressor will cease to supply the reservoir with compressed air. 55 To accomplish this purpose the governor mechanism includes a relief valve 7 which controls the passage of air from the pipe 5, here shown as a branch of the pipe 5, to a passage 9 leading to atmosphere, either direct 60 or through a pipe 10, said valve 7 being normally held closed by a spring 8 and being moved to open position by mechanism operable through variations in the pressure existing in the reservoir or system. 65

To effect the opening of the valve 7 a piston 11 is slidably mounted in a small cylinder 12 in the governor casing, said cylinder having a head 13, here shown in the form of a disk sweated into the casing, the piston having a cylindrical projection 14 working in a centrally disposed opening in the head 13. This piston is actuated by compressed air from the system, and the passage of compressed air to the cylinder 12 is controlled by a primary air valve 15. 75

The air valve 15 is preferably of the needle type, mounted in a cage formed by a plug 16 in threaded engagement with the casing, said valve controlling the passage of air from a 80 centrally disposed conduit 17 in the plug to a transverse passage 18 which communicates with a passage 19 in the main casing leading to the upper end of the cylinder 12.

The seat 20 for the valve 15 is formed in 85 the upper end of the passage 17 and the valve is normally held against its seat by a spring 21 interposed between the enlarged lower headed end of the valve and a removable screw-plug 22.

The passage 17 is formed of two diameters, the larger one housing the lower end of the valve and the spring, and the upper one forming a guide bore for the stem of the valve 15, which stem has a flattened portion 23 to allow 95 passage of air through the upper part of the passage 17 past the seat 20 when the valve is open.

The plug 16 projects into a control chamber or reservoir 24 which has communication 100

with the passage 8' connected with the pipe 5' through a conduit 25, chamber 26 and a passage 28 controlled by a check valve 29. The passage 28 is formed in a removable screw-plug 30 and mounted in the casing between the chamber 26 and the reservoir 24, said chamber 26 having a screw-plug 31 closing its lower end and permitting insertion or removal of the plug 30.

A check valve 29 has a head adapted to seat against the upper end of the plug 30, and has its stem passing through the passage 28, with its lower end provided with a nut 32 to limit its movement, which nut has radially disposed grooves 33 therein to permit the passage of air from the chamber 26 to the conduit 28.

The reservoir 24 has a drain opening 24 closed by a removable screw-plug 35. When the compressor is functioning normally it will be noted that the control reservoir 24 will be charged with air at discharge or reservoir-pressure, since the air from the discharge pipe line 5 is then free to pass from said pipe to pipe 5', conduits 8' and 25, chamber 26 and passage 28, to the reservoir 24, said pressure serving to keep check valve 29 open. When the valve 15 is open the compressed air in the reservoir 24 passes therefrom through passages 17, 18 and 19 to the cylinder 12 and acts on the piston 11 to move same down to open the valve 7, the opening of said valve immediately reducing the pressures in the conduits 8' and 25 and chamber 26, thereby causing the check valve 29 to close, this movement of the valve 7 by the piston 11 being effected because the area of the piston 11 is greater than that of the head of the valve and consequently the differential pressure through the transmission of compressed air from the reservoir 24 to the cylinder 12 effects the opening of the valve 7 against the pressure on its head and the spring 8, and causes the check valve 29 to cut off the discharge of air from the reservoir 24 into the chamber 26.

The means for effecting the opening of the primary air valve 15 consists of a pin 36 engageable with the upper end of the valve 15 and extending through an opening in the plug 16 and projecting slightly beyond the same, said pin being engaged by a bell crank lever 37 which is pivotally mounted intermediate its ends on a pin 37' and is normally held in inoperative position by a spring 37''. This lever 37 not only serves to engage the pin 36 so as to open the valve 15, but is also a holding lever in that it serves to hold the valve 7 open when the other mechanism hereinafter described, and actuated by the pressure in the reservoir, actuates said lever 37.

An operating lever 38 is pivotally mounted on a pin 39 carried by ears on the governor casing 40 and is operated by a rod 41 which has a forked upper end 42 provided with a

pin 43 mounted in a hole 44 in said lever 38, said hole being larger than the pin to provide a lost-motion connection so that a pair of springs 45, connected to a pin 46 on said lever beyond the hole 44 and to studs 47 on the casing, may produce a quick and powerful throw to said lever relative to the pin 43.

The rod 41 is moved in one direction, that is, upward, by fluid-pressure-operated means, comprising a cap member 48 with which the lower end of said rod is in contact, and forming with an end plate 49 and a bellows 50, connected at one end to said cap and at its other end to said plate in a fluid-tight manner, a diaphragm or pressure chamber 51 in communication with the reservoir or tank, not shown, through a pipe 52. Thus,

when air is introduced into the chamber 51 from the reservoir, it will tend to move the cap member 48 upward or outward and hence move the rod 41 upward and cause the end of lever 38, with which it is connected, to swing upward past its fulcrum center and the springs 45 then pull in the opposite direction

to cause the lever to move down the amount of lost-motion referred to. The rod 41 is moved in the opposite direction by a spring 53 interposed between a part of the governor casing and a nut 54 on said rod, which spring causes said rod to move downwardly in op-

position to the pressure of the air in the chamber 51 and thus cause the end of the lever 38 with which it is connected to swing downwardly past its fulcrum center, and the springs 45 pulling in the opposite direction

cause the lever to move up, as shown in full lines in Fig. 1, the amount of lost-motion referred to. The tension of the spring 53 is adjusted to such a value that it holds the lever 38 in its upper or inoperative position

against the pressure in the chamber 51 until the reservoir pressure builds up to a certain predetermined maximum value. The free end of the lever 38 on its downward swinging movement engages the pin 36 to move the same and consequently the primary air valve 15 downwardly to open said valve

and hold it open when the pressure in the reservoir has attained a predetermined maximum value.

In order that the primary valve 15 will not be held open under slight deviations in pressure in the reservoir, a trigger or latch 55 cooperates with the bell crank lever 37. This latch 55 is in the form of a lever pivotally mounted at its lower end on a pin 56 carried by the casing and normally moved toward the lever 37 by a spring 57. The latch 55 has a notch 58 with which the pointed

free end 59 of the lever 37 engages, whereby said latch 55 holds the lever 37 in a valve-opening position when the operating lever 38 has moved said lever 37 to this position.

The lever 37 also has the function of holding the piston 12 in its lower or valve-open-

ing position when engaged by the latch 55, since the pin or projection 14 on the piston is in line with the lever and engaged thereby, and this is important since the action of the air in the reservoir 24 upon the piston 11 is only temporary, due to the limited capacity of the reservoir 24 and to the fact that further compressed air is not available after the discharge pipe 5 is open to atmosphere through the opening of the valve 7. Thus, the opening of the valve 15 by the lever 37 occurs first, followed by the opening of the valve 7 by the piston 11 and the holding of said valve 7 open by the lever 37, the function of the lever 37 being to open the primary air valve and then hold the main relief valve 7 in an open position until such time as the pressure in the reservoir has been reduced to a condition where it is again necessary to build up the pressure in the reservoir with more compressed air.

The latch or trigger 55 also has a curved or beveled face 60 at its upper end engaged by the end 61 of the lever 38 on its upward swinging movement so as to release said latch from locking engagement with the lever 37 and thus allow the primary air valve 15 to close and hence cut off the supply of compressed air to the cylinder 12 and permit the spring 8 to close the valve 7 since the pressure upon the piston 11 in the cylinder 12 is not maintained for any length of time due to seepage of air around the pin 36 and the projection 14 of the piston.

35 With the construction above described, when the pressure in the reservoir, and hence the chamber 51, reaches a predetermined maximum value, the diaphragm, including the member 48, moves the rod 41 upward and
40 swings the free end 61 of the lever 38 downward, the lever 38 upon swinging past its horizontal position being given a quick and strong throw by the springs 45 and coming in contact with the lever 37 swings the same down, first into contact with the pin 36 which opens the valve 15 thereby admitting compressed air to the cylinder 12, moving the piston 11 down with the consequent opening of the valve 7, and as the lever 37 continues
45 to move down it is engaged by the trigger or latch 55 which keeps it in position to hold the piston 11 and consequently the relief valve 7 open after the lever 38 moves away from the lever 37. Thus the continuously
50 running compressor simply draws in air and pushes out the air past its discharge valve into the pipe 5 and thence to atmosphere, as previously explained, until such time as the pressure in the system has dropped to a pre-determined minimum value, such that there
55 is less force on the diaphragm or member 48, which then permits the spring 53 to come into action and move the lever 38 in the opposite direction, causing the end 61 of said lever to swing upward when the lost-motion
60

again comes into play and the springs 45 again impart a quick and strong force to the lever to move said end of said lever against the upper end of the latch 55 to cause its release, which lever then moves to the disengaged position under the action of its spring 57 and the release of lever 55 also permits the spring 39 to move lever 37 upwardly away from the projection 14 and the pin 36, thereby permitting the valve 15 to seat itself and the spring 8 to return the valve 7 to a closed position with the consequent movement of the piston 11 to its upper position, thereby shutting off further venting of the compressed air from the pipe 5 through the pipe 5' to the passage 9, and under which conditions compressed air from the compressor then passes through the pipe 5 past the check valve 6 to the reservoir. Thus, the springs 45 serve to produce a quick action on the lever 37 to open the valve 15 and a similar quick action on the latch 55 to release the lever 37, and the opening of the valve 7 serves to reduce the power necessary to keep the compressor running, since under these conditions the compressor is only working against the resistance of the air in its travel past the discharge valve, usually spring-seated, of the compressor on its otherwise normal compressing stroke.

The studs 47 and similar studs 62 secure the removable cover 63 in place on the casing. The springs 37" and 57 are each held in place by having one end seated in an opening in the lever with which it is associated and the other end bearing against a plate 64 secured to the governor casing by a screw 65. 100

While the terms "downward" and "upward" have been used relative to the description of the direction of movement of the valves and the levers associated with them, it will be understood that such terms are only relative and that it is possible to place the governor in other than an upright position without interfering with its operation, it being understood that where the device is not placed upright a light spring may be associated with the check valve 29 to tend to close the same. 105 110

I desired it to be understood that this invention is not to be limited to any particular form or arrangement of parts except in so far as such limitations are included in the claims or made necessary by the prior art. 115

What I claim as my invention is:

mary valve open, and means responsive to pressure in the reservoir for moving said lever to a valve-opening position when the pressure in the reservoir reaches a predetermined limit.

5 2. In a compressor control, the combination with the discharge line of a compressor, of a relief valve in said line, fluid-pressure-operated means for opening said relief valve while the compressor is running, a primary valve for controlling the operation of said fluid-pressure-operated means, means for opening said primary valve and holding the relief valve in open position including a lever and a latch associated therewith, and means responsive to the pressure in the system for actuating said lever and releasing said latch.

10 3. In a compressor control, the combination with the discharge line of a compressor, of a relief valve in said line, a control reservoir communicating with said line, a check valve closing communication with said line when said relief valve is open, a cylinder, a valve-controlled passage between said reservoir and cylinder, a piston in said cylinder actuated by 15 the pressure in said reservoir for opening said valve against discharge line pressure, a control valve for said passage, and means responsive to pressure in the system for actuating said control valve.

20 4. In a compressor control, the combination with the discharge line of a compressor, of a relief valve in said line, a control reservoir communicating with said line, a check valve closing communication with said line when 25 said relief valve is open, a cylinder, a valve-controlled passage between said reservoir and cylinder, a piston in said cylinder actuated by the pressure in said reservoir for opening said valve against discharge line pressure, a control valve for said passage, and means responsive to pressure in the system for actuating said control valve, said means also including mechanism for holding said relief valve open until the pressure in the system reaches a 30 predetermined minimum value.

45 In testimony whereof, I affix my signature.
NIELS A. CHRISTENSEN.
